W. ANDERSON.

DOOR LOCK AND METHOD OF APPLYING THE SAME,
APPLICATION FILED MAY 19, 1921.

1,423,825.

Patented July 25, 1922.

INVENTOR

By *William Anderson*
W. W. Williamson Atty.

UNITED STATES PATENT OFFICE.

WILLIAM ANDERSON, OF NEWARK, NEW JERSEY.

DOOR LOCK AND METHOD OF APPLYING THE SAME.

1,423,825.

Specification of Letters Patent. Patented July 25, 1922.

Application filed May 19, 1921. Serial No. 470,877.

To all whom it may concern:

Be it known that I, WILLIAM ANDERSON, a citizen of the United States, residing at Newark, in the county of Essex and State 5 of New Jersey, have invented new and useful Improvements in Door Locks and Methods of Applying the Same, of which the following is a specification.

My invention relates to new and useful 10 improvements in door locks and the method of applying the same, and has for its object to provide an exceedingly simple and effective device of this character whereby a lock may be applied to a door without the use 15 of a brace and bit and chisel it being only necessary to use a saw thus overcoming the necessity of having to employ a high grade mechanism to apply the lock.

A further object of the invention is to 20 provide a lock casing and a face plate all of which are the same width as the door to which the lock is applied, said door having recesses cut therein the same shape as the lock casing and its face plate and covered 25 or enclosed by escutcheon plates.

Another object of the invention is to provide a lock which may be readily and quickly applied to a door without having to form a mortise in the door and to provide 30 means for running the lock in position.

A further object of the invention is to provide a lock of the character described having an escutcheon plate formed as a part of or one of the sides of the lock casing.

With these ends in view, this invention 35 consists in the details of construction and combination of elements hereinafter set forth and then specifically designated by the claim.

In order that those skilled in the art to 40 which this invention appertains, may understand how to make and use the same, I will describe its construction in detail, referring by numerals to the accompanying 45 drawing forming a part of this application, in which:—

Fig. 1, is a fragmentary perspective view 50 of the free edge of a door showing the same recessed for the application of a lock embodying my invention.

Fig. 2, is a front edge view of a portion 55 of a door showing my lock applied thereto.

Fig. 3, is a perspective view of a lock produced in accordance with my invention.

Fig. 4, is a fragmentary side elevation of

a door showing one of the escutcheon plates with the lock behind the same.

Fig. 5, is a perspective view of a different formation of lock in which an escutcheon plate is formed therewith. 60

In carrying out my invention as here embodied, 2 represents a door in the free edge of which is formed a lock recess 3 consisting of three parts of compartments, a casing compartment 4 and face plate compartments 65 5 one of which projects above the top of the compartment 4 the other below the bottom of said compartment and in that part of the door forming a rear wall of the compartment 4 are formed holes 6 which are small 70 and could be formed by a gimlet. This lock recess can be readily formed with a saw as will be understood by merely sawing into the door so as to make slots and then knocking out the material between the slots by 75 beating the same with a suitable tool such as a hammer, although if preferred after the saw slots have been formed a chisel can be used to remove the desired material.

By forming the lock recess in this manner 80 it overcomes the necessity of using a brace bit to bore into the edge of the door which in so doing often spoils or ruins the door for unless the hole is bored absolutely straight the bit may pierce one of the faces of the 85 door or pass so close to one of the faces as to leave a very thin veneer which is objectionable and the present method of applying a blind mortise lock is also tedious and lengthy all of which disadvantages are entirely overcome by the use of my invention. 90

In Fig. 3, I have shown a lock 7 the casing 8 of which fits within the compartment 4 of the recess 3 while the projecting ends of the face plate 9 carried by said casing 95 fit into the compartments 5 of said recess, said casing and its face plate being the same width as the door 2 in which the recess is formed. With the inner or rear wall of the lock casing are formed the anchoring pins 100 which register with the holes 6 when the lock is in place in the recess, said lock being fastened by suitable fastening devices such as screws which pass through the holes 11 and into the face plate and are threaded 105 into the woodwork of the door.

After the lock has been properly positioned either or both sides thereof may be covered and enclosed by an escutcheon plate 12 of any desirable material or any suitable 110

size and configuration the same being fastened to the door by means of screws 13 or their equivalent passing through the plate and into the door.

- 5 In Fig. 5, I have shown an escutcheon plate 14 formed as a part of the lock casing and preferably integral with said casing and its face plate but otherwise the construction is the same and the use is identical.
- 10 Where the escutcheon plate is formed with the lock casing, said plate is preferably used as the outside one making it necessary to produce such locks in rights and lefts and a separate escutcheon plate may be fastened to the door.
- 15 In either case or whether the escutcheon is formed as a part of the lock or as separate elements the lock to be applied to a door must be as wide as the thickness of said door or more particularly the face plate must be the same width as the thickness of the door to which it is applied in order that there shall be no cracks to mar the appearance of the door.
- 20 It is to be understood that I do not make any claim to a particular mechanism as this may be of any well known or desired con-

struction, but what I do claim is the combination of a lock casing of the same width as a door to which it is to be applied with 30 said door recessed from one face to the other at one edge and means in the form of escutcheon plates either formed as separate elements or integral with the lock casing for enclosing or partially enclosing said lock 35 casing.

Of course I do not wish to be limited to the exact details of construction as herein shown as these may be varied within the limits of the appended claim without departing from the spirit of my invention.

Having thus fully described my invention, what I claim as new and useful is:—

A door lock including a casing, a face plate carried thereby, anchoring pins projecting from the rear wall of said casing, in combination with a door recessed to receive said lock casing and face plate, and escutcheon plates disposed across said recess and secured to the door for enclosing the lock 50 casing.

In testimony whereof, I have hereunto affixed my signature.

WILLIAM ANDERSON.
